ABSTRACT OF THE DISCLOSURE

A method and apparatus for cleaning by subjecting articles simultaneously to impact and ultrasonically agitated solvent. The apparatus has a wash tank containing solvent, means in the tank ultrasonically agitating the solvent therein and means in the tank periodically impacting the articles to be cleaned while the solvent is ultrasonically agitated.

This invention relates to ultrasonic impact cleaners and particularly to a cleaner apparatus in which objects to be cleaned are subjected to impact forces while immersed in an ultrasonically agitated solvent.

The use of ultrasonically agitated cleaning baths has been practiced for a considerable period of time. For example, various objects are cleaned of grease and soil by using ultrasonically agitated baths of solvents such as Freon and the like. There are, however, many instances where the rate of soil removal is excessively slow due to large amounts of impacted grease and soil. This is particularly true in the case of complex or laminar structures such as ball and roller bearings, motor stators, armatures, transformer plates and the like. In such cases, the removal of grease and particulate soil is seldom successful by any presently practiced methods due to the slow rate of grease dissolution and the mechanical locking of particulate solids between tight surfaces.

I have found that impact forces in combination with ultrasonic forces in the presence of the usual solvents will clean such structures rapidly and thoroughly whereas neither, alone, will accomplish thorough cleanliness without exposure of the structures to damaging or extremely long cleaning periods.

Preferably I subject objects to be cleaned to impact forces while simultaneously immersing said objects in an ultrasonically agitated solvent. I preferably provide a wash tank containing solvent, means in said tank ultrasonically agitating said solvent, a container suspended in said tank carrying an object to be cleaned and impact means in said tank periodically impacting said container. A temperature controlling means is preferably provided in the tank to maintain the solvent at a selected temperature. Preferably a vapor rinse tank is provided adjacent the wash tank with a vapor condenser extending around both the wash and rinse tank to prevent escape of solvent vapors.

In the foregoing general description of my invention I have set out certain objects, purposes and advantages of my invention. Other objects, purposes and advantages of the invention will be apparent from a consideration of the following description and the accompanying drawings in which:

FIG. 1 is a front elevational view with panels open;

FIG. 2 is a section on the line II—II of FIG. 1;

FIG. 3 is a top plan view of the apparatus of FIG. 1.

Referring to the drawings I have illustrated a housing 10, containing a wash tank 11 and a vapor rinse tank 12 adjacent thereto and separated by a common wall

2

13. An immersible transducer 14 is provided in the bottom of the wash tank 11. The transducer 14 is connected to a generator 15 mounted in housing 10 of any usual design by conventional means. Heaters 16 are provided in the wash tank 11 and are connected to a source of electrical power by means of connections 17 and 18. The heaters are controlled by a tank thermostat 19. A pump 20 is connected by line 21 through strainer 22 to the bottom of tank 11 to deliver solvent from the tank 11 through manifold line 23 and valves 24, 25 and 26 to either the cooler 27 or the vapor rinse tank 12. The cooler 27 is cooled by circulating water from solenoid valve 28 at the cooling water inlet. The cooling water is discharged at outlet 29.

15. The vapor rinse tank 12 is provided with a heater 30 connected by terminals 31 to a source of power through safety reset thermostat 32.

A vertically movable shaker table 33 is provided in the wash tank 11 and is movable in guides 34 on the 20 sidewall of the tank. The table is connected by link 35 to a vertically movable slide assembly 36 mounted on and actuated by air cylinder 37 on housing 10 outside the tank 11. The air cylinder 37 is supplied with air from an external line 38 through a conventional air filter 39, pressure regulator 40 and lubricator unit 41. Articles to be cleaned are immersed in a basket 42 into solvent in wash tank 11 above shaker table 33.

In operation the articles to be cleaned are placed in basket 42 which is lowered into solvent in wash tank 11 30 at a preselected temperature. The solvent is agitated by transducer 14 to provide ultrasonic solvent cleaning. At the same time as the solvent is agitated the air cylinder 37 is cyclically operated to move the slide assembly 36 vertically up and down, carrying with it the table 33 35 which impacts against the basket 42 at the top of each stroke. This combination of impact and ultrasonically agitated solvent quickly removes even the most stubborn grease and soil.

While I have illustrated and described certain preferred practices and embodiments of my invention in the foregoing specification, it will be understood that this invention may be otherwise embodied within the scope of the following claims.

I claim:

1. A method of cleaning articles comprising the steps of treating the articles to be cleaned in a container therefor by subjecting the container to repeated impacts from a solid mass independent of the container of sufficient force to impart a change in direction to said articles and simultaneously subjecting said objects separately to an ultrasonically agitated solvent.

2. The method as claimed in claim 1 wherein the solvent is maintained at a substantially constant temperature.

3. An apparatus for cleaning objects to remove grease and particulate soil comprising a housing, a wash tank in said housing containing a solvent, means in said wash tank ultrasonically agitating said solvent, a container in said solvent adapted to contain an object to be cleaned, and impact means defining a solid mass independent of the container in said tank separate from the means ultrasonically agitating said solvent repeatedly impacting said container with a force sufficient to impart a change in direction to said container and the objects therein.

4. An apparatus as claimed in claim 3 wherein heating means are provided in said tank for heating said solvent.

5. An apparatus as claimed in claim 3 wherein the means for ultrasonically agitating the solvent is a transducer fixed to the bottom of the wash tank.

6. An apparatus as claimed in claim 3 wherein a vapor

rinse tank is provided within the housing adjacent the wash tank.

7. An apparatus as claimed in claim 6 wherein a coolant coil extends along the top of the wash tank and the vapor rinse tank.

8. An apparatus for cleaning objects to remove grease and particulate soil comprising a housing, a wash tank in said housing containing a solvent, means in said wash tank ultrasonically agitating said solvent, a container in said solvent adapted to contain an object to be cleaned, and impact means in said tank separate from the means ultrasonically agitating said solvent repeatedly impacting said container said impact means comprising a vertically movable shaker table in the wash tank adapted in its uppermost position to strike the container, an air cylinder connected to said table to move the same and a source of air cyclically operating said air cylinder.
